Primary Examiner—Louis S. Zarfas*Attorney, Agent, or Firm*—Banner, Birch, McKie & Beckett[57] **CLAIM**

The ornamental design for an outsole bottom, as shown and described.

DESCRIPTION

FIG. 1 is a bottom plan view of an outsole bottom showing my new design;

FIG. 2 is a cross sectional view of the sole as shown in section 2—2 of FIG. 1;

FIG. 3 is a cross sectional view of the sole as shown in section 3—3 of FIG. 1;

FIG. 4 is a cross sectional view of the sole as shown in section 4—4 of FIG. 1;

FIG. 5 is a cross sectional view of the sole as shown in section 5—5 in FIG. 1;

FIG. 6 is a cross-sectional view of the sole as shown in section 6—6 of FIG. 1;

The broken line showing of sole periphery in FIG. 2 is for illustrative purposes only and forms no part of the claimed design.
